UNITED STATES PATENT OFFICE.

FRANK SCHWARZ, OF CHICAGO, ILLINOIS.

DOOR-HINGE.

956,738.

Specification of Letters Patent.

Patented May 3, 1910.

Application filed August 21, 1909. Serial No. 513,983.

To all whom it may concern:

Be it known that I, FRANK SCHWARZ, a citizen of the United States, residing at Chicago, in the county of Cook and State of Illinois, have invented certain new and useful Improvements in Door-Hinges, of which the following is a specification.

This invention relates to improvements in door hinges and particularly refers to the combination of a door hinge and a door stop.

One of the objects of the invention is the construction of a door hinge forming a stepped spring stop for the door.

Another object of the invention is the construction of a hinge having a rack thereon and a spring arm engaging with said rack whereby the door to which the hinge is connected can be held at different points of its movement.

With the above and other objects in view the invention relates to improvements in door hinges consisting in certain combinations, constructions and arrangements of parts, clearly described in the following specification and clearly illustrated in the accompanying drawings, in which,

Figure 1 is a front elevation of the door hinge, Fig. 2 is a detail perspective view of a hinge part, Fig. 3 is a detail plan view of a hinge part, Fig. 4 is a transverse sectional view of the hinge, and Fig. 5 is a vertical sectional view of the hinge.

Referring to the accompanying drawings, which illustrate the invention 1 denotes a hinge member or pintle supporting body, which is formed from a blank as shown in Fig. 3, and is provided with laterally disposed pintle supporting extensions or arms 2 and 3, which are located on opposite ends thereof. The central portion 4 of the hinge member 1 is provided with openings 5 for screws or other devices and with a longitudinally disposed spring tongue 6, which is bifurcated at 7.

45 The extension or arm 2 is formed with an arcuate rack 8 and with an opening 9. The extension or arm 3 is formed with a recess 10, diagonally disposed thereon with relation to the central part 4, and located on the rear side thereof. A second hinge member 11 is secured by a connecting pintle 12 to the member 1, said member 11 being formed with extensions or arms on its opposite ends like the arms or extensions on the hinge member 1. The arm 2' of the hinge mem-

ber 11 is disposed against the lower side of the hinge arm 3 of the member 1, and the arm 3' of said member 11 is disposed under the arm 2 of the hinge member 1. The member 11 is also provided with a spring 60 arm 6, like that of the spring arm of the member 1, and also with openings 5.

A spring stop member or rod 13 is secured to the arm or extension 2, with its upper end located in the opening 9 and its lower end engaging the rack 8' of the member 11, the rod 13 being held against the rack by the spring arm 6, as shown in section in Fig. 5. The recess 10' of the arm 3' of the member 11 engages the rod 13 at 14. 70 On the member 11 a second rod 15 is located. This rod is secured in an opening in the arm 2', said rod extending diagonally upward to engage the rack 8 of the arm 2, of the member 1, and engaging the spring 75 arm 6', which serves to normally hold the same in engagement with the rack 8. The arm 15 engages the recess 10 of the arm 3 at 16.

When the door to which the hinge is attached is moved the rods 13 and 15 of the members 1 and 11 will be moved into engagement with different teeth of the racks 8 and 8', and should it be desired to fix the door at any point this will be accomplished 85 by the spring rods 13 and 15 engaging with said racks 8 and 8'. Should the rods 13 and 15 become worn out so as to render poor service they may be easily replaced by removing the same from the arms to which 90 they are connected. Should it be desired to dispense with the spring stop rods 13 and 15 in order that the hinge may be temporarily used as an ordinary hinge the rods can be removed from the end arms. 95

Having described my invention I claim and desire to secure by Letters Patent,—

1. In combination, a door hinge comprising two hinge members pivotally connected together, one of said members having an 100 arm, said arm being provided with a rack, and a spring rod carried by the other member engaging with the rack.

2. In combination, a door hinge comprising two hinged members, each of said members being provided with a rack, and spring rods carried by the members engaging the racks. 105

3. In combination, a door hinge comprising two hinged members, one of said mem- 110

bers having an arm formed with a rack, and a rod carried by the other member engaging with said rack.

4. In combination, a door hinge comprising two hinged members, one of said members being formed with an arm having a rack thereon, a rod carried by the other member engaging with said rack, and a spring arm carried by said last member en-
10 gaging the rod.

5. In combination, a door hinge member comprising a central portion and two end laterally disposed arms, one of said arms being provided with a rack formed thereon, a
15 spring arm formed with a bifurcated end

arranged on the central part of said member, a second hinge member having a central part and two laterally disposed end arms, a pintle connecting the end arms of the members, said second member having a spring 20 arm located on its central part and a rack on one of its end arms, and rods secured to the members engaging the racks of the end arms.

In testimony whereof I affix my signature, 25
in presence of two witnesses.

FRANK SCHWARZ.
